US00D936109S

(12) **United States Design Patent** (10) Patent No.: **US D936,109 S**
(45) Date of Patent: **** Nov. 16, 2021**

(54) **SPREADER**

(71) Applicant: **OMS Investments, Inc.**, Los Angeles, CA (US)

(72) Inventors: **Paul E. Hsu**, Lewis Center, OH (US); **Ryan R. Berger**, Columbus, OH (US); **Daniel Wisniewski**, Columbus, OH (US); **Johannes Hertrich**, Columbus, OH (US); **John Knittle**, Westerville, OH (US); **Eric Glassner**, Hilliard, OH (US)

(73) Assignee: **OMS Investments, Inc.**, Los Angeles, CA (US)

(**) Term: **15 Years**

(21) Appl. No.: **29/765,012**

(22) Filed: **Jan. 5, 2021**

Related U.S. Application Data

(63) Continuation of application No. 29/699,097, filed on Jul. 23, 2019, now Pat. No. Des. 909,421, which is a continuation of application No. 29/595,095, filed on Feb. 24, 2017, now Pat. No. Des. 860,261.

(57) **CLAIM**

The ornamental design for a spreader, as shown and described.

DESCRIPTION

FIG. 1 is a front perspective view of a spreader showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The line shading in FIGS. 1-8 represents contour and not surface ornamentation. The broken lines illustrate the portions of the spreader that form no part of the claimed design.

1 Claim, 8 Drawing Sheets
